ALEXANDER Q. NASH

By *Benjamin R. Newcomb*
his Attorney

UNITED STATES PATENT OFFICE.

ALEXANDER Q. NASH, OF KANSAS CITY, MISSOURI.

HORIZONTAL OIL-BURNER.

1,303,578.

Specification of Letters Patent. Patented May 13, 1919.

Continuation in part of application Serial No. 141,877, filed January 11, 1917. This application filed May 2, 1917. Serial No. 166,008.

To all whom it may concern:

Be it known that I, ALEXANDER Q. NASH, a citizen of the United States, residing at Kansas City, in the county of Jackson and

5 State of Missouri, have invented certain new and useful Improvements in Horizontal Oil-Burners, of which the following is a full, clear, and exact description, such as will enable others skilled in the art to which it appertains to make and use the same.

10 My invention relates to burners and especially to that general class of burners which may be adapted or constructed for the burning of fuel oils such as kerosene, gasoline, crude oil and other heavy hydrocarbon oils; this application being a continuation in part 15 of applicant's co-pending application Serial No. 141877, filed January 11, 1917, Patent No. 1225994, granted May 15, 1917.

20 The present invention provides a burner of the above described class which is of such construction that it may readily replace the usual grate structure in the common furnace or cook-stove or may even be inserted above 25 the grate.

It further provides a burner which is back-fire proof by reason of the shape and location of the mixing and distributing chambers.

30 An added and most important feature of this burner is that a starting trough is made integral and co-extensive with the sides of the burner and vertically above that is located a retort tube having a U-shape with 35 substantially parallel legs, each end of the tube being so assembled in connection with the burner appurtenances that, when it is desired to clean the retort tube it is only necessary to open each end of the said re-

40 tort tube in order to obtain complete access to the interior thereof.

Other objects and features will appear from the detailed description of a specific and preferred form of the burner illustrated 45 in the accompanying drawing in which:

Figure 1 is a top plan view of a burner of the horizontal type constructed according to the fundamental principles of my present invention.

50 Fig. 2 is an end view of the burner shown in Fig. 1.

Fig. 3 is a section view on the line 3—3 of Fig. 1.

Fig. 4 is a section view on the line 4—4 of Fig. 1; and

55

Fig. 5 is a side elevation of the damper.

In detail:

The burner comprises the substantially cylindrical shell or body A having corrugations 1 on its upper face each of which is 60 transversely slotted on the peak as shown at 2. The shell A has, on its interior, integrally cast ledges 3 which support a perforate baffle plate 4 dividing the cylindrical interior of the shell into a lower mixing 65 chamber B and an upper distributing chamber C; the said mixing chamber B has formed integrally therewith a gas injector tube 5 extending fairly well into the interior thereof and delivering toward the concave surface of the hemispherical end 6 of the shell A, a plug 7 closes the core hole in the end of said shell.

Along opposite sides of the shell A and cast integrally therewith in such location as 75 to be entirely out of the combustion zone of the burner are starting troughs 8 and 9 which are preferably filled with some non-combustible absorbent material 10 such as asbestos wicking.

80

At its rear end the burner shell A has a spot 11 upon which is mounted a bracket 12 and additional supports 13 are provided at the forward end of said shell. The bracket 12 and supports 13 serve to mount a retort 85 tube D of substantially U-shape and having legs 14 and 15 which are co-extensive with the starting troughs 8 and 9 respectively. The legs 14 and 15 are supported vertically above the starting troughs 8 and 9 and at 90 sufficient height so as to embrace the margin of the zone of combustion and lie partially within the edges thereof as shown in Fig. 3. The said legs 14 and 15 contain very thin wire strands 16 which may be 95 pulled out of the ends of the legs in order to clean the latter. These wire strands serve to break up the particles of hydrocarbon as it becomes volatilized and gasified in the retort tubes.

100

At the forward end of the shell A is mounted a damper box E which is provided with a rectangular opening 17 which, toward its end, merges into a round opening 18 registering with the mouth of the fuel injector tube 5. The forward end of the

105

shell A also carries the supports 13 for the retort tube D. The bottom of the opening 17 slopes slightly as shown at 19 so as to feed any residual unvaporized oil toward 5 the burner instead of permitting it to drip outside and also, to insure against dripping, an upturned lip 20 is provided. Hinged to the damper box E on lugs 21 is a damper 22 which closes the end of the damper box E 10 and is adjusted by a screw 23 working in a threaded member 34 on the side of the damper box and having its end 35 engaging an ear 36 on the damper 22 and thus, as the adjusting screw 23 is turned by the thumb 15 knob 37 the damper leaf 38 is moved to or away from the opening in the damper box thereby giving more or less air draft as the case may be. The damper box E is apertured as at 39 and the damper leaf 38 is 20 slotted as at 40 for purposes to be herein-after set forth.

In connection with the burner described in preceding paragraphs I use my regulating valve F which forms the subject matter 25 of a separate application filed April 6, 1917, Serial No. 160080. This valve sets over the aperture 39 in the damper box and down into said damper box and the damper leaf 38 is slotted as above described at 40 to permit the damper to move. The said valve F is connected by a nipple 41 to a double T 42 on leg 15 of the retort tube D and the free arms of the double T 42 are closed by plugs 43 and 44 which may be removed to permit 30 ready access to the retort tube D for cleaning the same.

The remaining leg 14 of the retort tube D is provided with a T 45 having an inlet 46 connected with the source of fuel supply and 40 the T 45 embodies a fuel supply control valve operated by a knob 47 on the valve stem 48, the stem being packed by a stuffing box 49 adjusted from the stuffing box nut 50, said valve being removable to permit 45 cleaning.

In operation:

The burner is initially started by saturating the wicking in the starting troughs 8 and 9 and igniting the same, then the oil 50 flowing through the retort tube is heated by the flame emanating from the said starting troughs and as it is vaporized passes through the valve F and into the mixing chamber B, the gaseous mixture becomes a 55 more homogeneous mass by contact with the curved walls and end of the semi-cylindrical interior of the mixing chamber and finds its way upwardly into the distributing chamber C through perforations in the baffle plate 4, said perforations being fewer at the end adjacent the end 6 of the burner shell for the reason that the volume of gas is greater at this point due to the impact 60 against the end of the shell and thus in 65 order to make the flow into the distributing

chamber uniform throughout the length of the burner the number of perforations in the baffle plate 4 is considerably reduced at this location or, if desired, any arrangement of holes may be provided, either smaller or differently located, which will distribute uniformly the flow of gas to the distributing chamber C.

In order to clean the retort tube it is only necessary to remove the plug 43 and T 45 75 when the wires 16 may be withdrawn from the legs 14 and 15 or, if desired only plug 43 may be removed and air pressure applied at 46 will blow all sediment or carbon accumulation out of the retort tube. 80

While, in the foregoing, I have described a specific form of the present invention it is nevertheless to be understood that, in practice, I may resort to such practical modifications as fall within the scope of the 85 appended claims; also, it is to be noted that my burner is not strictly confined to use with liquid fuels.

I claim:

1. In an oil burner, a hollow cylindrical 90 burner head, a laterally extending baffle internally dividing said head into a lower mixing chamber and an upper distributing chamber, and means embodied in one end of said chamber and forming a part of the wall 95 thereof for introducing gas thereto at a point intermediate the ends.

2. In an oil burner, a hollow cylindrical burner head closed at one end by a wall having a hemi-spherical curvature, a perforate 100 baffle internally dividing said head into a lower mixing chamber and an upper distributing chamber said baffle having fewer perforations near the hemi-spherical end of the said head, and means embodied in and 105 forming a part of the wall of said mixing chamber for introducing gas thereinto.

3. In an oil burner, a burner head having a horizontally disposed injecting tube, an open end damper box registering with said 110 injecting tube and embodying means to direct any surplus fuel toward the interior of the burner head.

4. In an oil burner, a burner head having a horizontally disposed injecting tube, an 115 open end damper box registering with said injecting tube and embodying means to prevent outside drip of any surplus fuel oil.

5. In an oil burner, a burner head having a horizontally disposed injecting tube, a 120 damper box registering with said injecting tube and embodying a sloping bottom to direct any surplus fuel toward the interior of the burner head.

6. In combination with a burner head, a 125 damper box having an open outer end, a damper leaf hinged to said box and projecting in front of said outer end and having an upturned lug on the end opposite said damper box opening, and screw means car- 130

ried by the damper box and engaging said lug to move said damper leaf.

7. In an oil burner, a hollow head provided with a semi-cylindrical upper surface having corrugations slotted to form flame gaps, a trough arranged on each side of the head and each filled with absorbent material to hold a starting fluid, and a U-

shaped non-jointed retort tube substantially co-extensive with and arranged vertically above said troughs for feeding hydrocarbons to the hollow head.

In testimony whereof I have herewith set my hand.

ALEXANDER Q. NASH.
